UNITED STATES PATENT OFFICE.

EUGENE J. RAY, OF BEVERLY, MASSACHUSETTS, ASSIGNOR TO UNITED SHOE MACHINERY CORPORATION, OF PATERSON, NEW JERSEY, A CORPORATION OF NEW JERSEY.

BUTTONHOLE-SEWING MACHINE.

Application filed September 16, 1920. Serial No. 410,672.

The invention relates to stay cord trimming mechanism for that type of sewing machines commonly used for sewing buttonholes or similar short seams.

5 Buttonhole sewing machines of the type to which the invention is more particularly applicable comprise an upper thread mechanism and an under thread mechanism provided with means for guiding a stay cord into position to be covered by the overseam. The devices which have heretofore been provided for trimming the stay cord at the completion of each seam have not proved satisfactory, largely because the same severing, 10 or the same severing and holding device acts on both the stay cord and on the comparatively fine upper and under threads which at the completion of the sewing lead from the work to the under thread mechanism and are closely associated with the cord. The presence of the comparatively 15 large cord renders the grasp of the holding device on the fine threads uncertain and results in frequent failure to properly hold the under thread at the beginning of the seam. In case no provision is made for holding the under thread a sufficient length of such thread must be drawn through the needle eye before the cord and thread are 20 severed to insure the proper concatenation of the threads at the beginning of the next seam. This results in a long loose end of thread at the beginning of the seam, which 25 is objectionable.

30 The present invention avoids the above objections by the provision of a stay cord severing device which acts only on the stay cord and which leaves its supply end free and in position to be covered by the initial 35 stitches of the succeeding overseam. In cases where it is desirable to sever and hold the under thread, as well as to sever the stay cord as, for instance, in sewing buttonholes in clothing, the cord severing device 40 may be combined with additional severing and holding devices arranged to act only on the threads leading to the under side of the work and operating to sever and hold the 45 under thread.

50 The various features of the invention will be understood from an inspection of the accompanying drawings and the following detailed description of the mechanism illustrated therein.

In the drawings Fig. 1 is a plan view 55 partly in section showing so much of a buttonhole sewing machine as is necessary to illustrate the application of the present invention thereto; Fig. 2 is a partial end elevation; Fig. 3 is a detail plan view of the 60 cord and thread severing devices; Fig. 4 is a sectional detail substantially on line 4—4, Fig. 3; Fig. 5 is a view similar to Fig. 3, showing the parts in a different position, and Fig. 6 is a sectional view on line 6—6, 65 Fig. 5.

In the drawings the invention is shown applied to the buttonhole sewing machine shown and described in Patent No. 1,063,880, 70 dated June 3, 1913. The stitch forming mechanism of this machine comprises an upper needle 2, an under needle 4, and a looper 6. The under needle and looper are mounted on a turret 8, which also carries 75 the throat plate 10 provided with the usual hole for the passage of the needles and with the usual guide for the stay cord. The work clamp comprises the work supporting plates 12 and 14 mounted on the clamp carriage 16, and the vertically movable clamp arms 18 80 mounted on the plates and carrying the clamping jaws 20. The clamp carriage is moved from cutting to sewing position before the sewing starts, is moved during the sewing to feed the work, and is moved back 85 from sewing to cutting position after the sewing is completed, and the stitch forming mechanism is rotated during the sewing as 90 fully described in said patent.

At the completion of a buttonhole the upper thread may be cut and held above the work by the thread cutter and holder of Patent No. 1,094,896, dated April 28, 1914, leaving a waste loop of upper needle thread 95 which extends from the end of the seam forward over the throat plate and down around the looper. The under needle thread also leads from the end of the seam forward over the throat plate and down to the under needle, which at this time is immediately below the loop of upper needle thread. The cord leads from the end of the seam forward over the throat plate and down through the cord guide, which is so located in the throat plate 100 that it is somewhat further forward than the edge of the hole over which the threads pass. The point at which the cord enters the throat plate is, therefore, slightly sep- 105

arated from the point at which the threads enter and this is taken advantage of in separately severing the cord and leaving its end to be covered by the succeeding seam.

5. The cord is separated from the threads and severed in the construction shown by a cutter bar 22 provided at its forward end with a separator point or finger 24 arranged to pass over the throat plate and between the cord and threads. The cord is directed by the finger into the throat of a hook 26 on the cutter bar, which carries the cord laterally against the sharp edge of a cutter plate 28 secured to the work plate 12. The edge of the cutter plate is so located in relation to the cord guide in the throat plate that a free end of cord is left projecting into position to be covered by the initial stitches of the succeeding seam. The 10 cord may be thus severed without affecting the under thread, which may lead from buttonhole to buttonhole on the under side of the work if so desired.

It is frequently desirable to cut and hold 25 the under thread as well as to cut the cord and this may be done by providing the cutter bar 22 with a second hook 30 arranged to collect the threads and draw them laterally over a holding plate 32 and then against 30 a cutter plate 34. The hook 30 cooperates with the plate 32 to clamp the threads and cooperates with the plate 34 to sever the threads close to the under side of the work. The thread holder plate 32 and cord cutter 35 plate 28 are preferably formed as a single plate, as shown. The edge of the plate is rounded where it underlies the hook 30 so it will not sever the threads, and is also preferably notched as at 36 to retain the 40 threads under the hook.

The cutter bar is guided in a plate 38 secured to the work plate 12 and is operated by means of a slide 40, which is cylindrical in cross section and is mounted in a boss 42 at the outer edge of the plate. The slide is connected with the cutter bar through a pinion 44 engaged by a rack 46 on the bar and by a rack 48 secured to the slide. The slide is forced by a spring 50 in a direction 45 to hold its forward end against a stop 52 secured to the plate 38 as indicated in Fig. 1. When the slide is in this position the cutter bar is in its retracted position with the hook 26 overlying the cutter plate 28 and with the hook 30 overlying the holder plate 32.

The position of the parts at the beginning of a buttonhole making cycle is indicated in Figs. 1, 5 and 6. At the end of the previous cycle the cord was severed and the under thread as well as the loop of upper thread was severed, and the under thread is now held between the finger 30 and plate 32. At the beginning of the buttonhole making cycle the buttonhole slit is cut and the clamp carriage is moved forward to bring the but-

tonhole into sewing position and then the sewing mechanism is started. After the initial stitches of the seam have been formed the forward end of the slide 42 engages a finger 54 which is adjustably secured to the base plate of the machine and during the continued forward movement of the clamp carriage the slide 42 is pressed rearward with relation to the clamp carriage and plate 38, and advances the cutter bar into the position indicated in Fig. 3, thus carrying the thread and cord engaging hooks to the opposite side of the openings in the throat plate. The cutter bar is held in this position against the force of the spring 50 by a latching pawl 56 arranged to engage a notch 58 in the side of the slide. The latch continues to hold the slide and cutter bar against the pressure of the spring 50 until the buttonhole has been completed and until the clamp carriage has nearly completed its rearward movement from sewing to button-hole cutting position. Immediately after the work clamp has been opened to release the work the rearward movement of the clamp carriage brings the tail of the pawl 56 against an adjustable stop 59 so that the pawl is disengaged from the slide 40. The spring 50 acts to quickly retract the cutter bar so that the hooks 26 and 30 engage the 90 cord and threads close to the under side of the work and draw them together with the work laterally until the cord engages the edge of the cutter plate 28 and is severed, while the threads are carried between the plates 32 and 34 and are severed and held as indicated in Figs. 5 and 6. The end of the under thread, as well as a waste loop of upper thread, is held by the hook 30 and plate 32 until after the beginning of the 95 next sewing operation, when they are released by the forward movement of the cutter bar in re-setting it for its next cutting and holding operation.

While it is preferred to employ the specific construction shown and described, particularly in applying the invention to the machine of the patent above referred to, it will be understood that this construction and arrangement is not essential to the 110 broader features of the invention and may be varied or modified as found desirable or best suited to the construction and mode of operation of the machine to which the invention is to be applied.

What is claimed is:

1. A sewing machine having, in combination, overseam sewing mechanism comprising upper and under thread mechanisms and means for delivering a stay cord to the 125 under side of the work to be covered by the overseam, and a cord severing device acting only on the cord between the work and under thread mechanism.

2. A sewing machine having, in combina- 130

- tion; overseam sewing mechanism comprising upper and under thread mechanisms and means for delivering a stay cord to the under side of the work to be covered by the overseam, a cord severing device acting only on the cord between the work and the under thread mechanism, and devices for severing the under thread below the work.
5. A sewing machine having, in combination, overseam sewing mechanism comprising upper and under thread mechanisms and means for delivering a stay cord to the under side of the work to be covered by the overseam, a cord severing device acting only on the cord between the work and the under thread mechanism, and devices for severing and holding the under thread below the work.
10. A sewing machine having, in combination, overseam sewing mechanism comprising upper and under thread mechanisms, a throat plate and means for delivering a stay cord to the under side of the work to be covered by the overseam, a cord severing device acting to sever the cord alone between the throat plate and work, and to leave a free projecting end in position to be covered by the initial stitches of the succeeding overseam.
15. A sewing machine having, in combination, overseam sewing mechanism comprising upper and under thread mechanism, a throat plate and means for delivering a stay cord to the under side of the work to be covered by the overseam, devices for severing and for holding the under thread between the throat plate and work, and devices for severing the cord between the throat plate and work, and leaving a free projecting end in position to be covered by initial stitches of the succeeding overseam.
20. A sewing machine having, in combination, overseam sewing mechanism comprising upper and under thread mechanism, a throat plate and means for delivering a stay cord to the under side of the work to be covered by the overseam, and a cord severing device arranged to sever the cord between the throat plate and the work and provided with means for separating the cord from the under thread.
25. A buttonhole sewing machine having, in combination, stitch forming mechanism, means for delivering a stay cord to be covered by the seam, work holding means comprising a work supporting plate, and a cord cutting device mounted on the plate and acting at the completion of the seam to cut the cord alone and leave a free projecting end in position to be covered by the initial stitches of the succeeding seam.
30. A buttonhole sewing machine having, in combination, stitch forming mechanism including upper and under thread mechanisms, a work supporting plate, a cutter bar mounted on the plate and provided with a cord engaging throat, a thread engaging throat and a separator point between the throats, a cutter plate below the bar cooperating with the cord throat, and a cutter plate above the bar cooperating with the thread throat.
35. A buttonhole sewing machine having, in combination, stitch forming mechanism including upper and under thread mechanisms, a work supporting plate, a cutter bar mounted on the plate and provided with a cord engaging throat, a thread engaging throat and a separator point between the throats, a cutter plate below the bar cooperating with the cord throat, a holder plate below the bar cooperating with the thread throat, and a cutter plate above the bar cooperating with the thread throat.
40. A buttonhole sewing machine having, in combination, stitch forming mechanism including upper and under thread mechanisms, a work supporting plate, a bar mounted to slide on the plate and provided with two hooks for engaging the thread and cord respectively, and plates secured to the work plate cooperating with one hook in severing the cord and with the other hook in severing and holding the thread leading from the work to the under thread mechanism.
45. A buttonhole sewing machine having, in combination, stitch forming mechanism including upper and under thread mechanisms, a main frame, a work clamp carriage movable with relation to the frame provided with work supporting plates, thread trimming mechanism on one of the plates, a spring for actuating the mechanism, means operated by the travel of the carriage for setting the mechanism during the sewing, and means operated by the travel of the carriage for releasing said mechanism at the completion of the sewing.
50. A buttonhole sewing machine having, in combination, stitch forming mechanism including upper and under thread mechanisms, a throat plate, means for delivering a stay cord to be covered by the overseam, a work clamp carriage movable lengthwise of the buttonhole, a work supporting plate on the carriage, a cutter bar mounted on the plate and provided with thread and cord en-

- gaging throats, cutting and holding plates secured to the work plate at one side of the throat plate, mechanism for moving the bar during the sewing to position the throats on the side of the throat plate opposite to the cutting and holding plates, and means for moving the bar in the opposite direction after the completion of the sewing.
14. A buttonhole sewing machine having, in combination, a stitch forming mechanism comprising upper and under thread mechanism, a throat plate and means for delivering a stay cord to the under side of the work to be covered by the overseam, a clamp carriage comprising a work supporting plate, a cutter bar mounted to slide on the plate, cutting and holding plates arranged to co-operate with the bar, a slide carried by the work plate and connected to advance and retract the bar, a spring for forcing the slide in one direction, a fixed stop for moving the slide in the opposite direction during the travel of the clamp carriage, a latch for holding the slide in retracted position, and a stop for releasing the slide as the clamp carriage completes its travel.
15. A sewing machine having, in combination, stitch forming mechanism including upper and under thread mechanism, a throat plate, a work plate, a cutter bar on the upper side of the work plate, a transverse guide on the upper side of the work plate in which the bar slides, a hook on the bar arranged to be carried laterally across the throat plate by the reciprocation of the bar, and a cutter plate on the work plate over which said hook passes.
16. A sewing machine having, in combination, overseam sewing mechanism comprising upper and under thread mechanisms, a throat plate provided with a guide for delivering a stay cord to the under side of the work to be covered by the overseam, devices for engaging the cord and thread between the work and throat plate mounted to move in the direction of movement of the cord through the guide, and devices for severing the cord and thread.
17. A buttonhole sewing machine having, in combination, stitch forming mechanism including upper and under thread mechanisms and means for delivering a stay cord to the under side of the work to be covered by the overseam, a main frame, a travelling work clamp carriage movable with relation to the frame provided with work supporting plates, spring actuated devices on one of the plates for severing the cord and threads between the under thread mechanism and the work, means for setting said devices by the travel of the work carriage during sewing, a retaining latch for said devices, and means for tripping said latch by the travel of the carriage to release said devices after the completion of the sewing.
